US0D1108286S

(12) **United States Design Patent** (10) **Patent No.:** **US D1,108,286 S**
(45) **Date of Patent:** **** Jan. 6, 2026**

(54) **WATCH DIAL**

(71) Applicant: **Montblanc-Simplio GmbH**, Hamburg
(DE)

(72) Inventor: **Seila Alvarez Peña**, Neuchâtel (CH)

(73) Assignee: **Montblanc-Simplio GmbH**, Hamburg
(DE)

(**) Term: **15 Years**

(21) Appl. No.: **29/928,792**

(22) Filed: **Feb. 15, 2024**

Related U.S. Application Data

(63) Continuation of application No. 29/832,660, filed on Mar. 29, 2022, now Pat. No. Des. 1,020,487.

(30) **Foreign Application Priority Data**

Feb. 7, 2022 (WO) WIPO113204

(57) **CLAIM**

The ornamental design for a watch dial as shown and described.

DESCRIPTION

FIG. 1 is a front, perspective view of a watch dial showing my new design;

FIG. 2 is a front view thereof;

FIG. 3 is a rear view thereof;

FIG. 4 is a left side view thereof;

(Continued)

FIG. 5 is a right side view thereof;
 FIG. 6 is a top view thereof; and,
 FIG. 7 is a bottom view thereof.
 The drawings include shadows and reflections which indicate contour, not surface ornamentation.
